Primary Examiner — Terry A Wallace(74) *Attorney, Agent, or Firm* — Wilson Sonsini Goodrich & Rosati(57) **CLAIM**

The ornamental design for a thermoelectric beverage cooler, as shown and described.

DESCRIPTION

FIG. 1 is a top perspective view of a thermoelectric beverage cooler in accordance with the present design;

FIG. 2 is a front view of the thermoelectric beverage cooler;
FIG. 3 is a back view of the thermoelectric beverage cooler;
FIG. 4 is a right-side view of the thermoelectric beverage cooler;

FIG. 5 is a left-side view of the thermoelectric beverage cooler;

FIG. 6 is a top view of the thermoelectric beverage cooler; and,

FIG. 7 is a bottom view of the thermoelectric beverage cooler.

The broken lines shown in FIGS. 1-7 form no part of the claimed design.

1 Claim, 7 Drawing Sheets(56)
